UNITED STATES PATENT OFFICE

172,409

DRINKING GLASS

Hyman J. Warsager, Newark, N. J., assignor to
Ceraglass Inc., Newark, N. J., a corporation of
New Jersey

Application September 3, 1953, Serial No. 26,726

Term of patent 14 years

(Cl. D36—8)

To all whom it may concern:

Be it known that I, Hyman J. Warsager, a citizen of the United States of America, residing in the city of Newark, county of Essex, and State of New Jersey, have invented a new, original, and ornamental Design, for a Drinking Glass, of which the following is a specification, reference being had to the accompanying drawing, forming part hereof.

Figure 1 is a perspective view of a drinking glass, showing my new design;

Figure 2 is a perspective view thereof rotated 120 degrees clockwise; and

Figure 3 is a perspective view thereof rotated 240 degrees clockwise.

I claim:

The ornamental design for a drinking glass, as shown.
